[57] CLAIM

The ornamental design for a package for a contact lens, as shown and described.

DESCRIPTION

FIG. 1 is a perspective view of a contact lens package showing our new design;

FIG. 2 is a top plan view thereof;

FIG. 3 is a rear elevational view thereof; the left elevational view being identical thereto; the front and right elevation views being mirror images thereof;

FIG. 4 is a bottom plan view thereof; and,

FIG. 5 is a bottom perspective view thereof.
